ATTORNEY.

UNITED STATES PATENT OFFICE.

RALPH S. JENNINGS, OF BALTIMORE, MARYLAND.

VENEER FABRIC.

SPECIFICATION forming part of Letters Patent No. 241,865, dated May 24, 1881.

Application filed February 16, 1881. (No model.)

To all whom it may concern:

Be it known that I, RALPH S. JENNINGS, of Baltimore city, State of Maryland, have invented certain new and useful Improvements 5 in Veneer Fabrics; and I hereby declare the same to be fully, clearly, and exactly described as follows, reference being had to the accompanying drawings, in which—

Figure 1 is a plan of the fabric; Fig. 2, a sec-
10 tional view of the same.

My invention has for its object to provide a veneer fabric adapted for use in many connec-
15 tions—such as for seats for outdoor chairs or settees, for coverings for cotton-bales or other baled goods, or for the manufacture of pack-
ing-cases. I here mention these widely-dis-
similar uses to which the fabric is peculiarly
fitted as indicating the scope of its adaptability,
20 leaving other uses to suggest themselves,
as they will, after the following description of
the construction of the fabric.

In the drawings, A is a textile fabric, and B, C, and D are veneer sheets with the grain crossed. The fabric A is stitched or quilted to
25 the veneer, as shown at a.

In constructing a cotton-bale cover, I take the refuse burlap which is to be found in great quantities in the hands of paper-stock dealers,

and stitch the pieces together and to the veneer, forming a tough and strong material, which is 30 cut into shape to cover the bale, and when applied thereto protects the cotton from the dirt and mud of land transportation and from the bilge-water on shipboard. For use as a chair-seat or settee, I employ a fine cloth as the textile 35 fabric, neatly quilting it to the veneer, as shown in Fig. 1.

I am aware that veneer and textile fabric have been glued together to form chair-seats and similar articles, and that paper has been 40 stitched to felt, batting, and straw to form carpet-linings. Such I do not claim, and such are obviously not adapted to the uses to which my fabric is fitted.

What I claim is—

1. A veneer fabric consisting of one or more layers of wood veneer having a textile fabric stitched thereto, as set forth.
2. The fabric herein described, consisting of wood-veneer sheets stitched together with the 50 grain crossed and provided with a textile cover stitched thereto, as set forth.

RALPH S. JENNINGS.
